ATTORNEY

UNITED STATES PATENT OFFICE.

LOUIS S. RYSDON, OF CHICAGO, ILLINOIS.

VENTILATOR.

Application filed October 17, 1923. Serial No. 669,145.

To all whom it may concern:

Be it known that I, LOUIS S. RYSDON, a citizen of the United States, residing at Chicago, in the county of Cook and State 5 of Illinois, have invented new and useful Improvements in Ventilators, of which the following is a specification.

This invention relates to a ventilator and has for its primary object the construction 10 of a ventilator which will more efficiently ventilate a room and which will positively prevent downdrafts.

An object of the invention is the arrangement of the various passages so that 15 the circulation of outside air will facilitate the ventilation of a building.

A feature of the invention is the manner of arranging the various elements so that the circulation of outside air will tend to create 20 a vacuum in the throat of the ventilator to provide proper draft and in such a manner that outside circulating air will be positively prevented from entering the throat.

With these and other objects in view the 25 invention will be better understood from the following detailed description taken in connection with the accompanying drawing wherein:

Fig. 1 is a vertical sectional view of a 30 portion of a ventilator constructed in accordance with my invention.

Fig. 2 is a top plan view of a portion of a ventilator constructed in accordance with my invention.

Again referring to the drawing illustrating one of the many constructions of my invention the numeral 1 designates a body or casing of the ventilator forming a throat 2 and chamber 3. The chamber 3 may be 35 provided with or without a deflector 4. Extending downwardly from the casing and continuous thereof is an upper flange 5 while the lower flange 6 is similarly positioned so that between these flanges is formed a downwardly extending radial passage 7 that is subdivided by partitions 8 secured to the flanges. A vertical upper flange 9, a continuation of the flange 5, is formed, and in alignment with this flange 40 45 50

I arrange a vertical lower flange 10, a continuation of the flange 6. An outer band

11 is provided which is secured to the flanges heretofore described by the bracket 12. Thus it will be seen a vertical annular passage 13 is provided in communication with 55 the passage 7 in a manner that outside air may circulate through the passage 13 to create an action to draw air through the throat, chamber and passage 7. This is accomplished in a manner that outside air is 60 prevented from moving forward through the passage 7 to cause a downdraft. It will be apparent from the foregoing description that any downward draft will be prohibited due to the fact that the air passes through 65 the passage 13 either going upwardly or downwardly creating a draft it will draw air outwardly through the passage 7 from the interior of the casing. This circulation of air through the annular passage or chamber 13 will reduce to a minimum the inlet of air through the passage 7 and create a suction or draft to draw the air outwardly from within the casing 2.

To complete the invention I provide drain 70 75 holes 14 at the proper points.

It is, of course, to be understood the invention may be constructed in various other manners and the parts associated in other relations, therefore, I do not desire to be limited in any manner except as set forth in the claim hereunto appended.

Having thus described my invention what I claim is:

A ventilator comprising a casing forming 85 a throat, and a chamber above the throat, a deflector in the chamber, an annular upper flange extending from the casing downwardly, a lower annular flange extending from the casing downwardly and parallel to the 90 other flange to form a downwardly extending passage, partitions supported by the said flanges to sub-divide said passage, an inner vertical flange extending upwardly from said upper flange, a lower inner flange 95 extending from said first mentioned lower flange, and an outer band supported by said upper and lower flange and forming a vertically extending annular passage in communication with said first passage. 100

In testimony whereof I affix my signature.
LOUIS S. RYSDON.
